UNITED STATES PATENT OFFICE.

JOHN F. O'CONNOR, OF CHICAGO, ILLINOIS, ASSIGNOR TO WILLIAM H. MINER, OF CHAZY, NEW YORK.

FRICITION DRAFT-RIGGING.

1,374,677.

Specification of Letters Patent. Patented Apr. 12, 1921.

Application filed February 4, 1920. Serial No. 356,345.

To all whom it may concern:

Be it known that I, JOHN F. O'CONNOR, a citizen of the United States, residing at Chicago, in the county of Cook and State 5 of Illinois, have invented a certain new and useful Improvement in Friction Draft-Rigging, of which the following is a full, clear, concise, and exact description, reference being had to the accompanying drawings, 10 forming a part of this specification.

This invention relates to improvements in friction draft riggings.

One object of the invention is to provide a friction draft rigging for railway cars of 15 that type employing transversely arranged springs wherein high capacity is obtained.

More specifically, the object of my invention is to provide a friction draft rigging wherein the friction devices are disposed 20 outside of the draft sills and the spring resistance disposed between the sills.

In the drawing forming a part of this specification, Figure 1 is a vertical longitudinal sectional view of a portion of a rail- 25 way car showing my improvements in connection therewith. Fig. 2 is a horizontal sectional view corresponding substantially to the line 2—2 of Fig. 1, all of the parts being shown in normal or full release position. Fig. 3 is a vertical transverse sectional view corresponding substantially to the line 3—3 of Fig. 1. And Figs. 4 and 30 5 are detailed perspectives of two of the elements employed in the construction.

In said drawing, 10—10 denote channel shaped center or draft sills of a railway car arranged in the usual manner. A portion of a draw bar is indicated at 11 and the same is connected by a front transversely extending key 12 with a cast yoke 13.

Applied to the outer sides of the draft sills 10 are stop castings A—A, each of which is provided with a front stop shoulder 14, and a rear stop shoulder 15. The height 45 of each casting A is made such that they are fitted between the upper and lower flanges of the draft sills, as clearly indicated in Fig. 3. The castings A—A and the draft sills are provided with aligned sets of slots 50 16, 17, 18 and 19. The slots 16 accommodate the front key 12 to permit forward and rear movement of the latter and the slots 19 accommodate a rear key 20 and permit forward movement thereof within the slots. The two 55 intermediate slots 17 and 18 accommodate

pressure transmitting lugs, hereinafter described.

The spring resistance of the draft rigging is located between the sills and, as shown, comprises two springs B—B arranged transversely of the sills and each of which may be of the well known "Class G" type. Said springs B—B are confined between two followers 21—21 extending parallel to the sills but normally spaced therefrom. Each of 65 said plates 21 is provided on its inner face with suitable spring-centering lugs 22 and on its outer face with recessed bosses 23 to receive pressure transmitting lugs 24 extending through the slots 17 and 18 and preferably formed integrally with laterally movable friction shoes C.

The friction devices proper are duplicated on the outer sides of the draft sills. Each of said friction devices comprises a 70 front wedge D, a rear wedge E, an outer friction shoe F and an inner friction shoe C, heretofore mentioned. The wedges and friction shoes of each friction device are provided with coöperating wedge faces 25 80 so arranged that as the wedges D and E approach each other relatively, the friction shoes C and F will be laterally separated. Followers are provided in connection with each of the wedges D and E. The follower 85 arrangement associated with each wedge D consists of an L-shaped block 26 having one end thereof adapted to abut the stop shoulder 14 and the other end 27 to form a seat for the wedge D. Associated with each 90 block 26 is a T-shaped member 28 indicated in Fig. 5, the same having the web or shank thereof slotted as indicated at 29 to receive the corresponding end of the key 12. The flanges of the T-shaped member 28 bear 95 against the laterally extended portion 27 of the block 26. As clearly indicated in Fig. 2, the blocks 26 are provided with elongated slots 30 to permit movement of the key 12 therein during draft at which time the blocks 100 26 remain stationary. To prevent separation of the parts associated with the key 12, suitable cotters 31 are preferably passed through the key 12 and the T-shaped members 28.

At the rear of the rigging associated with each wedge E is a rectangular follower block 32 which bears on its forward face against the wedge E and on its rear face against the stop 15. The blocks 32 are 110

recessed to accommodate the key 20 and are secured thereto by cotters 33. Preferably, an intermediate block 34 is mounted on the key 20 within the yoke 13 and the yoke and block 34 are held against lateral movement with respect to the key 20 by cotters 35-35 located as clearly indicated in Fig. 2.

In order to hold the friction shoes F 10 against lateral separation and at the same time permit them to move longitudinally as is necessary, I provide upper and lower wide plates 36 and 37 which straddle the draft sills 10 and are adapted to slide relatively 15 thereto. Said plates 36 are bolted or otherwise suitably rigidly secured to the shoes F as indicated by the bolts 38-38.

The operation is as follows: Assuming a buffering or inward movement of the draw 20 bar, the front key 12 will be forced rearwardly and it is evident that the rear key 20 will be held stationary because of the stops 15 and blocks 32. As the key 12 moves rearwardly, it carries with it the 25 front follower arrangements thereby forcing the two forward wedges D rearwardly. As the wedges D move rearwardly, they laterally separate each pair of friction shoes C and F, the shoes C being forced inwardly 30 relatively toward each other and thereby compressing the springs B-B. In addition to the lateral separation of the shoes C and F, they have additional longitudinal movement as they slide on the rear wedges 35 E and this longitudinal movement of the shoes C and F is accommodated by the plates 36 and 37. In addition to the friction generated between the wedges D and E on the one hand and the shoes C and F 40 on the other hand, friction is generated between the wedges D and the follower blocks 27 and between the wedges E and the follower blocks 32 inasmuch as the wedges D and E are also forced to move laterally 45 in addition to the longitudinal movement of the one or the other. There is thus obtained large frictional wearing area to increase the capacity of the draft rigging and also prolong its life. It is believed the release action and the action in the draft will be understood without detailed explanation, in view of the foregoing explanation of the 50 buffering action.

With my construction, it is evident that 55 the draft sills are not subjected to any transverse or lateral strains from either the friction devices or the spring means and consequently the draft sills are required to withstand only those strains imposed by the 60 longitudinal pressure supplied to the stops 14 and 15. Furthermore, by locating the friction devices outside of the sills, I am enabled to make them of such size as may be advisable to obtain the necessary frictional capacity and wearing qualities, that 65

is to say, I am not limited in the size of my friction devices as is true where the same are to be found between the draft sills inasmuch as the spacing between the draft sills is limited in commercial practice to 12 $\frac{1}{2}$ 70 inches. This fact is of considerable importance in view of the constantly increasing capacity demanded of draft riggings as the cars and trains are made heavier and heavier.

Although I have herein shown and described what I now consider the preferred manner of carrying out the invention, the same is merely illustrative and I contemplate such changes and modifications as 80 come within the scope of the claims appended hereto.

I claim:

1. In a railway draft rigging, the combination with draft sills; of spring means disposed between the sills; friction devices entirely located outside of the sills and all the elements of which are longitudinally movable; and means operatively interposed between said friction devices and spring means 85 so arranged that the spring means afford a yielding resistance for said friction devices.

2. In a railway draft rigging, the combination with draft sills; of transversely arranged springs located between the sills; friction devices located outside of the sills, each of said devices including a friction element movable transversely of the sills; and pressure transmitting members interposed 95 between said laterally movable friction elements and the springs.

3. In a railway draft rigging, the combination with a draw bar, yoke acting means, and follower acting means having operative portions disposed between and outside 105 of the sills; of friction devices located outside of the sills; spring means disposed between the sills; and pressure transmitting means interposed between the friction devices and the spring means, said sills being 110 free from lateral strains from either the friction devices or the spring means.

4. In a railway draft rigging, the combination with draft sills; of spring means located between the sills; duplicate friction 115 devices located on the outer sides of the draft sills, each of said devices including a pair of laterally separable friction shoes; and means operatively interposed between the inner laterally movable friction shoes 120 and the spring means.

5. In a railway draft rigging, the combination with draft sills; of a friction device on each outer side of the draft sills, each of said friction devices including relatively 125 longitudinally movable end wedges and a pair of relatively laterally movable friction shoes; spring means located between the draft sills; and pressure transmitting means extending through the sills and interposed 130

between the friction shoes and the spring means.

6. In a railway draft rigging, the combination with draft sills, a draw bar, a yoke, and front and rear transversely extending keys; of friction devices interposed between the outer ends of the keys; and spring means located between the said friction devices and also between the keys, said 10 spring means being operatively associated with the friction devices.

7. In a railway draft rigging, the combination with draft sills having stops on the outer sides thereof; of friction devices disposed on the outer sides of the sills; followers coöperable with said stops and between which the friction devices are interposed; a draw bar; yoke acting means; spring means located between the sills; 20 pressure-transmitting means interposed between said spring means and the friction devices; and means interposed between said followers outside of the sills and the draw bar and yoke acting means whereby longitudinal movements of the draw bar are communicated to the friction devices.

8. In a railway draft rigging, the combination with draft sills; of upper and lower plates straddling the draft sills; friction 30 shoes rigidly secured to the outer ends of said plates outside of the draft sills; spring

means located between the sills; friction wedges and shoes coöperatively associated with said first named friction shoes; and pressure transmitting means extending 35 through the sills and interposed between the friction devices and the spring means.

9. In a railway draft rigging, the combination with draft sills, having stops on the outer sides thereof; of spring means located 40 between the sills; followers on the outer sides of the sills coöperable with said stops; a draw bar; a yoke; keys operatively associated with the draw bar and yoke and extending outside of the sills and operatively 45 associated with the followers; friction devices on each outer side of the draft sills, said friction devices being interposed between the corresponding pair of followers and each including an outer friction shoe, 50 an inner friction shoe, a front wedge, and a rear wedge; pressure-transmitting means extending between said spring means and the inner friction shoes of said friction devices; and upper and lower plates extending 55 over and beneath the draft sills respectively, connected at their outer ends to said outer friction shoes.

In witness that I claim the foregoing I have hereunto subscribed my name this 14th 60 day of Jan., 1920.

JOHN F. O'CONNOR.
